UNITED STATES PATENT OFFICE

2,621,434

STAMP TRANSFERRING MECHANISM

Ernest W. Jackson, Austin, and Marvin S. Burke,
Alpine, Tex., assignors to The Steck Company,
Austin, Tex., a corporation of Texas

Application July 21, 1950, Serial No. 175,277

8 Claims. (Cl. 41—1)

1

Our invention relates to an improved mechanism to transfer stamps, such as water-released decal revenue stamps, from a web to a series of objects to be stamped, such as cigarette packages.

The revenue laws of many states require that tax stamps be affixed to packages of cigarettes. Since the stamps must be affixed in great numbers, with the consequent requirements of time and labor, it is highly desirable to provide machinery capable of efficiently performing this operation. However, it is also highly desirable to provide machinery of a relatively portable nature capable of meeting the requirements of a specific locality, since the stamps used in different places vary and as a consequence the most practical time to apply stamps is after the cigarettes reach the locality of sale.

The apparatus of the present invention fulfills the foregoing requirements in a new and improved manner in that it is highly efficient in operation, applies stamps rapidly to the packages in automatic fashion and is of small size, low cost, and simple, to the end that it can be used effectively by unskilled operators in small scale local enterprises.

It is therefore a general object of the present invention to provide an improved stamp applying machine.

Another object of the present invention is to provide an improved stamp applying machine characterized by small size, simplicity, and low cost.

Further it is an object of the present invention to provide an improved stamp applying machine capable of transferring decal type stamps securely carried by a web of paper or the like from the web to the objects to be stamped in automatic fashion and in the face up position.

Still another object of the present invention is to provide a highly positive mechanism to withdraw decal stamps from a web and to deposit the same on the objects to be stamped.

The novel features which we believe to be characteristic of our invention are set forth with particularity in the appended claims. Our invention itself, both as to its organization and method of operation, together with further objects and advantages thereof, will best be understood by reference to the following description taken in connection with the accompanying drawings, in which:

Figure 1 is an end elevational view of an apparatus constructed in accordance with the present invention;

Figure 2 is a cross-sectional view through axis 2—2, Figure 1, showing the stamp-carrying web in place;

2

Figure 3 is an enlarged fragmentary side elevational view like Figure 2, showing the transfer wheel;

Figure 4 is a cross-sectional view through axis 5 4—4, Figure 3; and,

Figure 5 is a fragmentary plan view of the web upon which the stamps are carried and the belt carrying the web.

Referring to Figures 1 and 2, the mechanism 10 comprises a base plate 10 carrying upright pairs of frame defining posts 12, 14, and 16. A pair of longitudinal bars 18 extend between each pair of posts 16 and 14 as shown.

15 A conveyor belt for the objects to be stamped is indicated at 20, Figures 1 and 2. This belt is carried by the pulleys 22 which are supported on suitable posts 24 from the base 10. The belt 20 is driven in continuous uniform motion by the drive pulley 25 which is driven in accordance 20 with the motions of the other parts of the structure as described in further detail hereafter.

Cigarette cartons 26 on the belt 20 are shown in phantom in Figures 1 and 2. These cartons usually contain ten cigarette packages 27 arranged in five pairs as shown. The top of the carton is opened by suitable means (not shown) to expose the tops of the successive packages as they are carried in the carton 26 by the belt 20.

Transfer or carrier wheel 28 is journaled in 30 beams 30 which extend between the pairs of posts 12 and 14. This wheel is slightly wider than the packages 26 as shown in Figure 1 and its axis is transverse to the direction of motion of the cartons 26 and so spaced above the cartons 35 as to engage the same as described in detail hereafter. The carrier wheel 28 withdraws the stamps from the carrying web and deposits the same on the successive packages 27 in each carton 26.

40 A roller 32 is journaled in the cross bar 34 above and in line with the wheel 28. This roller engages the protruding stamp-carrying pads 36 of the wheel 28 as shown and carries the belt 37 which also extends over the guide roller 38 carried by the posts 16. Intermediate the rollers 32 and 38, the cross bars 18 carry a shallow tank 40 filled with water or other appropriate stamp loosening fluid. The belt 37 is guided into this tank by the relatively small guide rollers 42, 44, 45 46, and 48, as shown, these rollers being carried by suitable journals on the tank 40. Preferably the rollers 42, 44, 46, and 48 have central portions of reduced diameter to avoid damage to stamps on the web 54.

50 The roll 50, wound about mandrel 52, is made up of a web 54 carrying two series of spaced stamps. The arrangement of this roll is shown

in plan view in Figure 5. The web, indicated at 54, is of paper or like material and carries the stamps 51 on the outer face as seen in the roll 50. In the mechanism, the web 54 overlays the belt 37 over guide roller 38, into tank 40, and 5 over the roller 32. In the tank 40, the web is wetted and as a consequence of the wetting tends to stick to the belt 37 which is maintained in a damp condition by reason of its passage through the tank 40. The web 54 accordingly adheres 10 to the belt 37 as it travels over roller 32 and over the guide pulley 56 and does not peel off from the belt until the fixed separating knife 58 is reached.

The roller 32, wheel 28 and belt 29 are driven 15 in unison and at speeds such that the roller 28 rotates the distance between adjacent pads 36 when the objects being stamped (the cigarette packages 27, Figure 2) travel their center-to-center distance and during this time the roller 20 32 rotates the distance between two sets of stamps. It will be apparent, therefore, that the roller or wheel 28 will travel at a greater peripheral speed than the linear speed of the conveyor belt. Otherwise, the stamps could not be spaced 25 out around the circumference of roller 28 by a considerably greater distance apart than they are when traveling on conveyor belt 37. This is accomplished by the gears 60 and 62 which drive roller 32 from the wheel 28 and by the chain 64 which rides on sprockets on shafts 66 and 68, Figure 1, to rotate roller 25 in unison with the rotations of the wheel 28. The wheel 28 is driven by belt 66, Figure 1, from the motor 69 as shown.

In order to withdraw stamps positively from the web 54 and to deposit stamps positively on the packages 27, the stamp receiving pads 36 are arranged to attract the stamps as they engage the web 54 and to repel the stamps as they reach the packages 27. To this end the stamp carrying pads 36 are perforated as shown in Figure 1 to form a mesh of fine holes 70. Immediately underneath each pad a cavity 72 is provided as shown in Figure 4, the cavities for each pair of pads 36 communicating with an axial passage 74. These axial passages all extend to the side face 78 of the wheel 28 and open on the annular groove 76 therein. The groove 76 and passages 74 define an annular slip ring upon which the fixed suction and pressure pipes 80 and 82 ride 50 at the upper and lower diametrically opposed positions as shown.

The suction and pressure pipes 80 and 82 extend to the suction and pressure connections of the air pump 84, Figure 1. This pump is driven 55 by motor 69 and draws air into pipe 80 and forces it out of pipe 82.

At their ends, the pipes 80 and 82 terminate in brushes 84 and 86, respectively, which fit snugly in the annular groove 76 and ride snugly against the bottom face 76a of that groove. Preferably the brush 84 defines a tear drop shaped opening 84a, Figure 3, which wipes over the face 76a of the groove 76 to cause a rapid rise and slow decay of the suction pressure in each cavity 72 as its stamp carrying mesh 70 engages the web 54. Similarly, the brush 86 preferably defines a tear drop shaped opening 86a where it rides on the bottom 76a of groove 76 to provide a rapid buildup of pressure as the stamp carrying mesh 70 engages the package 27.

In order to index the web 54 relative to the roller 32 (and hence the wheel 28), the belt 37 carries a series of spaced protuberances 88, Fig-

ure 5, which are received in the corresponding index holes 90 in the web 54.

Operation

During operation of the mechanism of the drawings, the motor 69 is energized to turn the rotating mechanism and apply suction and pressure to pipes 80 and 82. Cartons 26 are placed on the belt 20 as it travels in response to the rotation of pulleys 22 so that a continuous succession of equally spaced cigarette packages 27 advance past the point A, Figure 2 (defined by the low point of travel of the wheel 28), at uniform velocity.

As the successive packages 27 travel past point A, the stamp carrying pads 36 of the wheel 28 (which are spaced circumferentially by the center-to-center spacing of the packages 27) engage the successive packages 27, since the peripheral speed of the wheel 28 equals the linear speed of the belt 20 by reason of the chain 64. Because of the equal linear velocities of the pads 36 and the packages 27, there is no slipping but merely formation of contact and its subsequent withdrawal. During the contact pressure is applied to the chambers 72 of each stamp carrying pad 36 to urge the stamp away from the wheel 28 and onto the packages 27. The pressure is applied at this point because the brush 86 is located to register with the corresponding passage 74 at this time.

The engagement between the pads 36 and the respective packages 27 is a non-wiping pressure engagement with the stamps being urged towards the packages. When the engagement is broken, the stamps are peeled off the pads 36 so that at any instant the stamp is being separated from the wheel 28 along only a single line and not over a large surface. As a consequence the stamp separates easily and is firmly affixed to the package.

The stamps are picked up by the stamp-carrying pads 36 of the wheel 28 by the contact between web 54 and these pads, which contact occurs at point B, Figure 2. Since the web 54 moves the relatively short distance between two stamps during the same time the wheel 28 rotates the much greater distance between adjacent pads 36, the latter move over the former with a wiping action, and since the pads 36 are relatively dry as compared to the wet surface of web 54, the stamps tend to adhere to the pads 36 and to slip relative to the web. In other words, belt 37 carrying web 54 thereon travels at a lesser speed than the peripheral speed of wheel 28. As indicated previously, this is accomplished by the driving ratio between gears 60 and 62, gear 60 being rigidly secured to shaft 66 on which wheel 28 is mounted, while gear 62 is rigidly fixed to the shaft on which roller 32 is mounted.

The circular configuration of the web 54 as it travels with belt 37 over roller 32, in conjunction with the circular configuration of the wheel 28, cause the pads 36 and the web 54 to travel diverging paths relative to each other, with the consequence that the stamps separate from the web and adhere to the pads 36. The suction applied to each pad at point B supplements and aids the tendency of the stamps to detach and assures a positive feed of each stamp from the web to the pad 36.

While the web 54 travels in a circular path at point B, thus giving a considerable diverging travel in relation to the pads 36, other conformations of belt 37 may be used in this region so long

as the resulting paths of movement diverge. One such path is formed by causing the belt 37 and web 54 to travel in a linear path at point E.

It will be observed that the pads 36, together with the cavities 72, define stamp carrying parts on the wheel 28 spaced by the center-to-center spacing of the packages 27.

The stamps 57 carried by the web 54 are shown in the drawing as bearing a simple cross marking. Of course, the particular marking forms no part of the present invention and will vary with the tax represented by the stamps. The web 54 may be of paper or like material and carries a water sensitive adhesive that becomes quite slippery when wet so that the individual stamps 15 (which are of water-resistant film-like material) may readily slide relative to the web.

If it is desired to accommodate the mechanism to packages 27 of varying height, adjustable elements may be provided to raise or lower belt 23 without varying its velocity of travel.

While we have shown and described a specific embodiment of the present invention, it will of course be understood that many modifications and alternative constructions may be made without departing from the true spirit and scope thereof. We therefore intend by the appended claims to cover all modifications and alternative constructions falling within the true spirit and scope of the appended claims.

What we claim as new and desire to secure by Letters Patent of the United States is:

1. In a mechanism for applying stamps to successive objects as they travel uniformly past a fixed point, the combination comprising a rotatably mounted wheel having on its peripheral surface a plurality of protruding stamp carrying pads, said pads being spaced circumferentially to correspond to the center-to-center spacing of the successive objects, a conveyor means spaced from said wheel for carrying said objects past said fixed point, said conveyor means being aligned with respect to said wheel to carry said objects past said wheel so that one of said stamp carrying pads is pressed against each of said objects at said fixed point, means for moving said conveyor means at a uniform linear speed, and means for rotating said wheel at substantially the same peripheral speed as the linear speed of said conveyor means.

2. In a mechanism for applying stamps to successive objects as they travel uniformly past a fixed point, the combination comprising a rotatably mounted wheel having on its surface a plurality of protruding stamp carrying pads spaced circumferentially in correspondence with the center-to-center spacing of the successive objects, said pads having convex surfaces with a plurality of perforations therethrough, said wheel having gas-filled interior passages communicating with the perforations in said pads, means for increasing the pressure of said gas within said passages to assist in disengaging the stamps from said pads, a conveyor means spaced from said wheel for carrying said objects past 65 said fixed point, said conveyor means being aligned with respect to said wheel to carry said objects past said wheel so that one of said stamp carrying pads is pressed against each of said objects at said fixed point, means for moving said conveyor means at a uniform linear speed, and means for rotating said wheel at substantially the same peripheral speed as the linear speed of said conveyor means.

3. In a mechanism for applying stamps to suc-

cessive objects as they travel uniformly past a fixed point, the combination comprising a rotatably mounted wheel having on its peripheral surface a plurality of convex stamp carrying pads spaced circumferentially by the center-to-center spacing of the successive objects, said pads having a plurality of perforations therein, said wheel having gas-filled interior passages communicating with said perforations and extending to a face of the wheel to provide a slip ring thereon, a fixed pressure pipe positioned to ride on the slip ring and communicate with the surface thereof to impart increased pressure to the gas in said passages to assist in transferring the stamps to the objects, a conveyor means spaced from said wheel for carrying said objects past said fixed point, said conveyor means being aligned with respect to said wheel to carry said objects past said wheel so that one of said stamp carrying pads is pressed against each of said objects at said fixed point, means for moving said conveyor means at a uniform linear speed, and means for rotating said wheel at substantially the same peripheral speed as the linear speed of said conveyor means.

4. In a mechanism for applying stamps to successive objects as they travel uniformly past a fixed point, the combination comprising a rotatably mounted wheel having on its periphery 30 a plurality of protruding stamp carrying pads, said pads having convex surfaces and being spaced circumferentially in correspondence with the center-to-center spacing of the successive objects, a continuous conveyor belt for depositing 35 stamps on said pads, said conveyor belt being aligned with respect to said wheel to carry said stamps past said wheel so that each of said stamp carrying pads is pressed against a stamp on said belt, means for moving said belt at a uniform linear speed, and means for rotating said wheel at a greater peripheral speed than the linear speed of said conveyor belt.

5. In a mechanism for applying stamps to successive objects as they travel uniformly past a fixed point, the combination comprising a rotatably mounted wheel having on its periphery a plurality of protruding stamp carrying pads, said pads having convex surfaces lying in a surface concentric to said wheel and being spaced circumferentially in correspondence with the center-to-center spacing of the successive objects, a second rotatably mounted wheel of smaller diameter than said first-mentioned wheel and aligned therewith so that the peripheries of said 55 wheels are adjacent at a point, a continuous conveyor belt for depositing stamps on said pads passing over said second-mentioned wheel and engaging said stamp carrying pads at the adjacent point of said wheel peripheries, means for rotating said second-mentioned wheel at a uniform peripheral speed, and means for rotating said first-mentioned wheel at a greater peripheral speed than the peripheral speed of said second-mentioned wheel.

6. In a mechanism for applying stamps to successive objects as they travel uniformly past a fixed point, the combination comprising a rotatably mounted wheel having on its periphery a plurality of stamp carrying pads spaced circumferentially by the center-to-center spacing of the successive objects, said pads having a plurality of perforations therein, said wheel having interior passages communicating with the perforations in said pad, means for reducing the gas pressure within said passages to assist in de-

positing stamps on said pads, a continuous conveyor belt for depositing stamps on said pads, said conveyor belt being aligned with respect to said wheel to carry said stamps past said wheel so that each of said stamp carrying pads is pressed against a stamp carried on said belt, means for moving said belt at a uniform speed, and means for rotating said wheel at a greater peripheral speed than the speed of said conveyor belt.

7. In a mechanism for applying stamps to successive objects as they travel uniformly past a fixed point, the combination comprising a rotatably mounted wheel having on its peripheral surface a plurality of convex stamp carrying pads spaced circumferentially by the center-to-center spacing of the successive objects, said pads having a plurality of perforations therein, said wheel having interior passages communicating with said perforations and extending to a surface of the wheel to provide a slip ring thereon, fixed suction and pressure pipes positioned to ride on the slip ring and communicate with the surface thereof to impart suction and pressure to the passages to assist in engaging and disengaging the stamps on said pads, a conveyor means spaced from said wheel for conveying said objects past said fixed point, said conveyor means being aligned with respect to said wheel to carry said objects along a tangential line past said wheel so that one of said stamp carrying pads is pressed against each of said objects at said fixed point, a continuous conveyor belt for depositing stamps on said pads, said conveyor belt being aligned with respect to said wheel to carry said stamps past said wheel so that each of said stamp carrying pads is pressed against a stamp on said belt, means for moving said conveyor means at a uniform linear speed, means for rotating said wheel at substantially the same peripheral speed as the linear speed of said conveyor means, and means for moving said belt at a
